UNITED STATES PATENT OFFICE.

RUDOLPH CONRADER, OF ERIE, PENNSYLVANIA.

METHOD OF AND APPARATUS FOR OPERATING OIL WELLS.

Application filed July 20, 1920. Serial No. 397,864.

To all whom it may concern:

Be it known that I, RUDOLPH CONRADER, a citizen of the United States, residing at Erie, in the county of Erie and State of Pennsylvania, have invented new and useful Improvements in the Method of and Apparatus for Operating Oil Wells, of which the following is a specification.

In the operation of oil wells if the gas pressure is entirely relieved on the well it will result in a momentary increased production but in the continued operation of the well the total production will be decreased. To get the maximum production the pressure should be maintained in the well and this pressure should be maintained practically constant.

It will be understood that most wells producing gas in any quantity are connected up with some gas system so that there is a varying back pressure at the discharge. The present invention is designed to hold the well under constant pressure which may be determined upon as accomplishing its maximum production and in the carrying out this invention this constant pressure is maintained regardless of the discharge pressure.

In the accompanying drawings I have shown an apparatus coming within the invention and exemplifying the method as follows:—

Fig. 1 is an end elevation of a controlling valve.

Fig. 2 a section of an oil well with a controlling valve in place thereon.

Fig. 3 an enlarged section of the controlling valve.

Fig. 4 an end view of the valve as shown in Fig. 3.

Fig. 5 a section of an alternative construction of valve adapted for controlling wells under a vacuum.

Fig. 6 an end view of the same valve.

1 marks the well which extends through the various earth formations to the oil sand, 2 the casing of the well, 3 the casing head, 4 the tubing, 5 the pump barrel, 6 the strainer leading to the barrel, 7 the usual cavity in the oil sand, 8 the pump plunger, 9 the sucker rod, 10 the walking beam or jack operating upon the sucker rod, 11 the oil discharge pipe, and 12 the gas discharge opening into the casing head. These parts are or may be of any desired construction following the usual practice. The controlling valve has a body 14 which is connected

with the discharge 12 by a nipple 13. The body connects to the discharge pipe 15 which leads to the line and is subjected to the varying pressures of the line.

A valve seat 16 is arranged in the body 14 and a valve 17 operates on this seat by a movement toward and from the seat. A stem 18 extends from the valve 17 to a diaphragm 19 which is sealed with relation to the body and exposed on its outer surface to the atmosphere. A spring 21 is arranged against the end of the stem 18 and an adjusting nut 22 is provided in the outer end of the cap 20 by means of which the spring 21 may be adjusted to vary the pressure at which the well is maintained.

With the spring properly set the face of the valve 17 being exposed to the well pressure the valve will open against the spring 21 when the pressure has reached the point to which the spring is adjusted and the well will discharge until its pressure has been brought to the pre-determined pressure and will be held at this pressure by the opening and closing of the valve through the opposing forces of the gases in the well and the spring. Where the well discharges to a line with a varying discharge pressure this disturbs the action of the device because this pressure will be exerted against the back face of the valve and will be added to the spring. To compensate for this the diaphragm 19 is provided which is subjected to the discharge pressure and the pressure on the diaphragm compensates for the pressure on the back of the valve so that regardless of discharge pressure there is a balanced relation of the valve.

If the tensioning up of the spring is too abrupt to accomplish the desired result the size of the diaphragm may be slightly varied to compensate for this. With wells which it is desired to maintain at a pressure below atmosphere a partial vacuum is maintained on the discharge line. A valve for controlling the well pressure is shown in Figs. 5 and 6. Here the valve structure is the same as in Fig. 3. A diaphragm is provided which is subjected to the reduced pressure and thus balances the valve. In this case the outside of the diaphragm is subjected to atmospheric pressure and the face of the valve exposed to well pressure is normally under atmospheric pressure. A spring 23 is secured to a projection 24 on the valve stem and a projection 25 on an adjusting screw 26. A

- 2
- nut 27 is provided for adjusting the screw 26, thus varying the tension of the spring. This adjustment may be set by a lock nut 28. As soon as the pressure in the well 5 rises above what is desired there will be a preponderance of pressure in the well over atmospheric pressure which preponderance added to that of the spring will open the valve and discharge gas from the well.
- 10 While I have stated that I maintain a constant pressure in the well it will, of course, be understood that this is practical constancy rather than theoretical and the device only operates with variations of pressure 15 but with such variations it does operate so as to maintain approximate constancy.
- What I claim as new is:—
1. The method of operating oil wells which consists in maintaining a constant pre-determined pressure on the well.
  2. The method of operating oil wells which consists in maintaining a constant pre-determined pressure above atmosphere on the well.
  3. The method of operating oil wells having a discharge into a medium having a varying pressure which consists in maintaining a constant pre-determined pressure on the well.
4. The combination with an oil well casing 30 of devices actuated by pressure in the well for maintaining a constant pre-determined pressure on the well.
5. The combination with an oil well casing 35 of devices actuated by pressure in the well for maintaining a constant pre-determined pressure on the well and means for compensating for variations of discharge pressure.
6. The combination with an oil well casing 40 of a valve controlling the discharge from the casing having its face exposed to well pressure; a counter-pressure device opposing the pressure in the well; and a compensating pressure device exposed to the 45 discharge pressure and compensating for the action of discharge pressures upon the valve.
7. The combination with an oil well casing 50 of a valve controlling the discharge from the casing and having its face exposed to well pressure; a spring opposing the opening of the valve; and a diaphragm exposed to discharge pressure and the action of the spring and valve for compensating for variations in pressure in the discharge.

55 In testimony whereof I have hereunto set my hand.

RUDOLPH CONRADER.
